DESIGN FOR A SCRAPER ATTACHMENT FOR LIVE BOOMS

Kenneth J. Kennedy, South San Francisco, Calif.

Application November 4, 1944, Serial No. 116,149

Term of patent 7 years

(Cl. D41—1)

To all whom it may concern:

Be it known that I, Kenneth J. Kennedy, a citizen of the United States of America, residing at South San Francisco, in the county of San Mateo and State of California, have invented a new, original, and ornamental Design for Scraper Attachment for Live Booms, of which the following is a specification, reference being had to the accompanying drawing, forming part thereof.

Fig. 1 is a rear perspective view of a scraper attachment for live booms, embodying my new design;

Fig. 2 is a top plan view thereof; and

Fig. 3 is a front elevational view thereof.

I claim:

The ornamental design for a scraper attachment for live booms, as shown.

KENNETH J. KENNEDY.
